UNITED STATES PATENT OFFICE.

JAMES BRUSH ANDERSON, OF PORTLAND, OREGON.

AEROPLANE-BRAKING DEVICE.

1,420,509.

Specification of Letters Patent. Patented June 20, 1922.

Application filed August 4, 1920. Serial No. 401,132.

To all whom it may concern:

Be it known that I, JAMES BRUSH ANDERSON, a citizen of the United States, and a resident of Portland, county of Multnomah, 5 and State of Oregon, have invented a new and Improved Aeroplane-Braking Device, of which the following is a full, clear, and exact description.

This invention relates to means for slowing the speed of an aeroplane, and has reference more particularly to an aeroplane having auxiliary propellers which are adapted to be rotated in a direction reverse to the direction of the main propeller so that the speed of the aeroplane will be decreased.

An object of this invention is to provide auxiliary propellers on an aeroplane which may be used to decrease the speed of the aeroplane when landing, and may also be used to obtain a quick "get-a-way" when rising from the ground.

Reference is to be had to the accompanying drawings forming a part of this specification, in which it is understood that the drawings illustrate one form of the invention with certain modifications, and in which—

Figure 1 is a front view of an aeroplane with my improved device in position.

Figure 2 is a front view of an aeroplane having a modified form of my device in position.

Figure 3 is a central sectional view through a second modified form of my invention.

Figure 4 is a horizontal central sectional view through the aeroplane showing the operating mechanism for my auxiliary propellers.

Figure 5 is a sectional view through the mechanism being taken on the line 5—5 of Figure 4.

Figure 6 is a sectional view through the mechanism being taken on the line 6—6 of Figure 4.

Referring to the accompanying drawing by numerals, 10 indicates the engine of an aeroplane having a main propeller 11, wings 12, wheels 13, and fuselage 14. The main propeller 11 is usually located midway between the ends of the wings 12, and when landing, the engine 10 is run at low speed but is not actually turned off since the machine would then be out of the control of

the operator. It is desirable to slow down 55 the speed of the aeroplane immediately before landing so that the landing will be accomplished with less risk to the aeroplane and to the pilot. For this purpose I provide a pair of auxiliary propellers 15, one 60 positioned on each side of the main propeller 11 and between the upper and lower wings 12. A tube 16 loosely fits around each of the auxiliary propellers 15, the forward and lower end of said tube being cut so as 65 to slope downwardly and rearwardly as shown in Figure 3, and said tubes are curved to conform to the shape of the wings thus increasing the lifting power of the aeroplane.

Each of the propellers 15 may be driven from an independent engine located in the fuselage or from the engine operating the main propeller 11 as shown in Figures 4 to 6 inclusive. If the auxiliary propellers 15 75 are operated from the main engine 10, the shaft 17 of said main engine will extend rearwardly and will be provided with a clutch 18 which may be operated by any suitable means so that the auxiliary propellers can be disconnected. A clutch (not shown) may be also provided on the shaft 17 adjacent the main propeller 11 so that said propeller may be disconnected when the auxiliary propellers 15 are in operation. 85 The shaft 17 extends rearwardly into a housing 19 and is provided on its end inside said housing with a bevel gear 20 meshing with a bevel gear 21 secured to a vertical shaft 22. The upper end of the shaft 22 extends 90 into a housing 23 and is provided with a bevel gear 24 meshing with a bevel gear 25 secured to a shaft 26.

The shaft 26 extends laterally through the fuselage 14 and each end extends into 95 one of the tubes 16. Each end of the shaft 26 is provided with a disc 27 which is mounted on said shaft so as to be capable of axial movement along said shaft but being constrained to rotate continuously with said 100 shaft 26. A shaft 28 is rotatably and concentrically mounted in each of the tubes 16 so that the axes of the shafts 28 are at right angles to the axes of the shaft 26.

A friction wheel 29 preferably of fibrous 105 material, is mounted on each of the shafts 28 adjacent the discs 27, said wheels being capable of axial movement along the shafts
